UNITED STATES PATENT OFFICE.

THOMAS D. CASSERLY, OF CHICAGO, ILLINOIS, ASSIGNOR TO ABRAM COX STOVE COMPANY, OF PHILADELPHIA, PENNSYLVANIA, A CORPORATION OF PENNSYLVANIA.

BOILER-FURNACE.

1,276,490.

Specification of Letters Patent. Patented Aug. 20, 1918.

Application filed December 14, 1917. Serial No. 207,150.

To all whom it may concern:

Be it known that I, THOMAS D. CASSERLY, a citizen of the United States, and a resident of Chicago, county of Cook, State of Illinois, 5 have invented certain Improvements in Boiler-Furnaces, of which the following is a specification.

My invention relates to certain improvements in boilers used for heating buildings, 10 either with hot water or steam, and the invention relates particularly to boilers consisting of cast iron sections having portions extending over the fire.

One object of my invention is to construct 15 a boiler of this type so that the products of combustion will be thoroughly consumed before entering the chimney. This object I attain by forming an overhead brick arch at the back of the fire box so that the major 20 portion of the products of combustion must pass under the arch prior to circulating through the flue spaces of the boiler.

A further object of the invention is to provide gas passages between the upper portion 25 of the arch and the overhanging portion of the boiler.

These objects I attain in the following manner, reference being had to the accompanying drawings, in which:

30 Figure 1 is a longitudinal sectional view of a boiler, illustrating my invention;

Fig. 2 is a transverse sectional view; and

Fig. 3 is a perspective view of the form of arch illustrated in Figs. 1 and 2.

35 1 is the base of the furnace. 2 is the grate. 3 are the intermediate cast boiler sections. 4 are the end sections of the boiler. These sections are made hollow and communicate with one another so as to allow the water to circulate freely through all of the sections.

40 Each of the intermediate sections has depending legs 5 at the rear and the side sections extend down to a point in line with the legs and form, with the intermediate sections, the walls of the fire chamber. The abutting ends of the several sections are recessed so that when assembled they form flues 6 and 7. The lower flue 6 communicates through a passage 8 with the combustion chamber and at its outer end with the upper flue 7 through a passage 9. The upper flue 7 connects with the down flue 10 formed in the back plate of the boiler which, in turn, communicates with the pipe leading

to the chimney. This construction, as above 55 described, is a type of boiler that was made prior to my invention.

In order to thoroughly consume the products of combustion in this type of boiler, I form a transverse arch 11, preferably of fire 60 brick, or other suitable non-combustible material, which is located a given distance from the back of the combustion chamber so as to form a comparatively narrow flue 12. This arch is vertically arranged and extends 65 into the space 14 formed by the tongues 15, which project from the overhanging portions of the boiler sections. The upper edge of the arch stops short of the top of the space so as to form gas passages 16, and the arch 70 is reduced at its upper edge so as to pass between two of the laterally projecting portions 17 of the tongues. The arch, in the present instance, is built in the furnace in any suitable manner, preferably by making 75 the fire brick sections and cementing them together. The arch is held by studs 18 projecting into the arch from the side sections of the boiler, as clearly shown in Fig. 2, but it will be understood that other means 80 of fastening the arch and its sections may be resorted to without departing from the essential feature of the invention.

The arch is comparatively narrow so as to provide a large, unobstructed combustion 85 chamber, and is of such a length that its lower edge preferably extends into the body of coal on the grate. The fire brick arch forms, in fact, the back of the main fire chamber and when the fire chamber is 90 charged with coal the flow is down under the arch, as shown in the drawings, the bed of coal being shallower at the back than at the front and the products of combustion, as they arise from the main body of coal, must 95 pass through the body of coal at the rear and under the arch so that the rear portion of the furnace is practically a down draft furnace, as there is not sufficient area in the gas 100 passages 16 above the arch to carry off the major portion of the products of combustion, consequently, the fire brick arch becomes very highly heated and aids in the thorough combustion of the fuel and as the body of coal beyond the arch is comparatively shallow, as shown in the drawings, a certain amount of heated air passes up through the 105 grate and through the shallow body of coal

from the ash pit and combines with the products of combustion passing under the arch. Therefore, the products of combustion are thoroughly consumed as they pass up the rear flue 12 and through the two horizontal flues 6 and 7 to the chimney flue.

By providing the gas passages 16 above the arch, the gas which would naturally accumulate in the upper portion of the combustion chamber freely escapes over the arch and combines with the products of combustion in the vertical flue 12 and is also thoroughly consumed in its passage through the horizontal flues.

15 As before remarked, the transverse arch 11 may be built up in the furnace or may be made in sections and secured in position in any suitable manner and, in some instances, may be made hollow and reinforced, 20 if found desirable. Any suitable means may be provided for admitting air from the ash pit to the rear flue back of the fire brick arch, but if the bed of fire at this point is shallow, as shown in the drawings, sufficient 25 air will be passed through the shallow body of fuel to properly consume the products of combustion.

While I have shown a particular form of boiler having an overhanging portion with 30 depending tongues directly over the fire, my invention can be applied to other types of water or steam boilers which are formed by assembling cast metal sections. The main feature of the invention is the forming of a 35 transverse suspended arch at the rear of the combustion chamber so as to form a back flue which causes the products of combustion to pass under the arch and through a portion of the fuel to the grate.

40 I claim:

1. The combination in a sectional boiler, of a grate; a series of intermediate sections and end sections, the intermediate sections extending over the grate and having depending 45 legs at the back, said sections having horizontal flues for the passage of the products of combustion in that portion extending over the grate; a separate transverse arch located in the combustion chamber under the 50 overhanging portions of the boiler and extending to a point directly above the grate and spaced from the rear of the boiler formed by the depending legs to form a ver-

tical flue which communicates with the horizontal flue.

2. The combination in a sectional boiler, of a grate; a series of intermediate sections and end sections, the intermediate sections extending over the combustion chamber and having flues therein and also having tongues 60 less in width than the sections and extending toward the grate; and an independent fire brick arch arranged transversely across the combustion chamber at a point some distance from the back of said chamber so as 65 to form a vertical flue between the back of the combustion chamber and the arch, said flue communicating with the flues in the boiler sections, said arch having portions projecting into the spaces between the 70 tongues and terminating short of the sections of the boiler so as to form narrow gas passages between the upper end of the extending portions of the arch of the boiler, said arch being of such depth that, under 75 normal conditions, it will extend into the upper surface of the fuel so that the products of combustion must pass under the arch and through a portion of the fuel into the rear flue.

3. The combination in a sectional boiler, of a base; a grate; a series of intermediate sections and end sections forming the boiler; longitudinal flues formed between the several sections, each of the intermediate sections having depending tongues less in width than the sections, each of the tongues having projecting portions spaced apart, each section also having legs, and the end sections extending down to a point on a line with the 85 legs and forming, with the legs, a combustion chamber, the lower flues in the overhead portion communicating with the combustion chamber at the rear; and a transverse fire brick arch extending across the combustion 90 chamber above the grate and at a distance from the back of the combustion chamber to form a vertical flue communicating with the said lower flue of the overhead portion of the boiler, said arch being notched to receive 100 the tongues of the overhead sections of the boiler, the portion between the notches being reduced in width; and means for securing the arch to the side sections of the boiler.

In witness whereof I affix my signature. 105
THOMAS D. CASSERLY.
